UNITED STATES PATENT OFFICE.

JOHN R. FLAHERTY, OF ST. LOUIS, MISSOURI.

OIL BURNER.

Application filed May 19, 1924. Serial No. 714,400.

To all whom it may concern:

Be it known that I, JOHN R. FLAHERTY, a citizen of the United States, residing at the city of St. Louis, State of Missouri, 5 have invented a certain new and useful Improvement in Oil Burners, of which the following is a specification, reference being had to the accompanying drawings, forming a part thereof.

10 This invention relates to a certain new and useful improvement in oil-burners and has for its chief object the provision of an oil burner that is relatively simple, inexpensive, and compact in form and construction and efficient and comparatively noiseless in operation.

With the above and other objects in view, my present invention resides in the novel features of form, construction, arrangement, 20 and combination of parts hereinafter described and pointed out in the claims.

In the accompanying drawings,

Figure 1 is an elevational view of an oil-burner embodying my invention;

25 Figure 2 is a vertical sectional view of the burner;

Figure 3 is a plan view of the burner;

Figure 4 is a similar view partly broken away and in section and with the oil-vaporizing disk and fan omitted;

30 Figure 5 is an enlarged fragmental view, showing the motor, fan, oil-vaporizing disk in section;

Figure 6 is a plan view of the fan of the 35 burner; and

Figure 7 is an inverted plan view of the burner-parts of Figure 5.

Referring now more in detail and by reference characters to the drawings, which 40 illustrate a preferred embodiment of my invention, 1 designates the base of the burner, which is preferably in the form of a hollow frusto-conical casting cut-away or apertured, as at 2, for purposes shortly appearing, and recessed at its upper margin, as at 3, to provide an annular seat for a ring-shaped lower shell-member 4 flanged and shouldered at its upper margin, as at 5, to, in turn, provide an annular seat for a second ring-shaped or 45 companion shell member 6 and for the preferably obliquely disposed legs 7 of a fourth casting 8 for the most part encircling the upper shell-casting 6, as best seen in Figure 1. The legs 7 are preferably disposed in 50 the plane of the inner periphery of the casting 8 and are obliquely continued upwardly

upon the inner periphery of the casting 8 to provide spacers 9, for concentrically spacing the casting 8 from the encircled casting 6, the casting 8 preferably flaring outwardly 60 at its upper margin, as at 10. Below the horizontal plane of the outer casting 8, the encircled casting 6 is formed with a series of cut-outs to provide the shell with a plurality of air-inlets or apertures, as at 11.

65 Disposed in spaced relation within, and integrally joined by connecting-lugs 12 to the lower shell-casting 4, is a water-basin 13 formed in its end-wall with an out-let 14 communicating with a water exhaust-pipe 15 70 leading through the base-aperture 2 to a suitable place of discharge.

75 Disposed over, and supported by means of inwardly projecting lugs 16 on the shell-member 4, is a water-retaining or cap-member 17 apertured in its end wall, as at 18, for purposes shortly appearing.

80 Seated in and projecting through the basin 13 at approximately its axial center, is a tubular-member or stem 19 that extends at its upper end through the aperture 18 to adjacent the upper margin of the encircled upper shell-casting 6 and at its lower end has communication with a pipe 20 leading from a suitable source of crude-oil or 85 other fuel supply (not shown).

90 Fixed on the stem, is a suitable bearing-collar 21, and disposed on the stem 19 and supported preferably for anti-friction rotation by the collar 21, as best seen in Figure 5, 95 is a tubular casting 22, preferably integral with which, at its lower end and disposed preferably somewhat above the horizontal plane of the upper margin of the basin 13, as best seen in Figure 2, is a so-called water-wheel or turbine 23 comprising an annular series of suitable spaced blades 24. Leading through the base-aperture 2 and the end-wall of the basin 13, as best seen in Figure 2, from 100 a suitable source of water-supply (not shown), is a water-pipe 25 having its discharge or nozzle-end 26 disposed in close proximity to the blades 24, as best seen in Figure 4, which blades, as seen in Figures 4 and 5, are preferably dished or concaved 105 both longitudinally and transversely to effect a substantially noiseless so-called rolling impingement engagement of the discharging water.

110 Carried by and suitably fixed to the upper end of the casting 22, is a disk 27 formed within its area with an integral series of

fan-blades 28. Also disposed around the stem 19 and thread-seated at its lower end, as at 29, upon and to rotate with the casting 22, is a tubular-extension 30, fixed upon which adjacent its upper end is a burner-disk 31 formed with a multiplicity of annular perforations 32 and an annular series of approximately or so-called moon-shaped openings 33.

10 Connected to the upper end of the stem 19 by a T-coupling or the like 34, and disposed horizontally over the rotatable burner-disk 31, as best seen in Figures 2 and 3, is a stationary discharge pipe 35 provided 15 with a series of discharge-orifices 36; and coiled within the upper shell-casting 6 with its one or lower end communicating, as at 37, with the water-supply pipe 25 and its upper end discharging through a reduced 20 or jet orifice 38 upon the burner-plate or disk 31, as seen in Figures 2 and 3, is a water-heating coil 39.

In use and operation, the crude oil or other fuel supplied to the stem 19 discharges 25 through the outlet-orifices 36 of pipe 35 upon the rotating burner-disk 31, where either as liquid or vapor it is ignited, and where the various openings 32 and 33 effect a breaking up and spreading of the fuel. At the same 30 time, under the force of water discharging upon the blades 24 under suitable pressure through the nozzle-outlet 26 of the water supply pipe 25, the casting 22 and its carried fan 27 and burner-disk 31 are rotarily actuated upon the stem 19, some of such water supply discharging through the nozzle-outlet 38 upon the burner-disk 31 in a thin stream or jet initially cold and subsequently, after the burner has been in operation, as 40 hot water and steam. The apertures 11 in the upper shell member 6 permit the entrance of air, which, under the action of the fan-blades 28, the latter being arcuated at their edges and largely upset to extend obliquely 45 to the rotating plane of the fan-disk, is forced upwardly through the openings of the disk 31 and thoroughly mixed with the discharging liquid or vapor fuel, effecting, in association with the discharging water 50 or steam, a burning of the crude oil with a clear, white, hot flame and substantially total combustion of the fuel without carbon and smoke. Due also to the novel form of the fan-blades 28 and of the disk 31, the 55 fuel is largely centripetally acted upon and driven inwardly towards the supply pipe or stem 19, whereby more or less intense heating of such pipe and its discharging fuel and consequent ready combustion thereof are obtained. I may add that the enclosing shell member 8, which at its upper margin projects above the plane of the shell 6, functions to confine the flame and direct the same and the heat thereof upwardly through the furnace, stove, or other heating 60

structure within which the burner may be arranged, the base aperture 2 and the spaces between the basin 13 and shell 4 furnishing additional inlets for air to the fan 27 and the burner-disk 31. I might also state that, 70 due to the obliquely disposed legs 7 and their extensions 9 and the obliquely disposed openings 11 in the ring or shell-member 6, the air is given a so-called rolling movement as it is drawn into the shell under the 75 action of the fan 27, which, I have found, greatly facilitates combustion.

My new burner is relatively simple in form, may be constructed at low cost, and is exceedingly efficient in the performance of 80 its intended functions.

I am aware that changes in the form, construction, arrangement, and combination of the several parts of the burner may be 85 made and substituted for those herein shown and described without departing from the nature and principle of my invention.

Having thus described my invention, what I claim and desire to secure by Letters Patent is:

1. An oil-burner comprising a shell, a burner-disk having a multiplicity of openings mounted for rotation within the shell, means for effecting rotation of the disk, and means including a stationary pipe provided lengthwise with a series of discharge orifices disposed horizontally over the disk for supplying fuel to the disk. 95

2. An oil-burner comprising an apertured shell, a burner-disk having a multiplicity of openings mounted for rotation within the shell, a rotary fan disposed in spaced relation under the disk, means for effecting rotation of the disk and fan, and means including a pipe provided lengthwise with a series of discharge orifices disposed horizontally over the disk for supplying fuel to and upon the disk. 100

3. An oil-burner comprising an apertured shell, a flat burner-disk provided with a multiplicity of openings mounted for rotation within the shell, a rotary fan disposed in spaced relation under the disk, means for effecting a rotation of the disk and fan, and means including a pipe provided lengthwise with a series of discharge orifices disposed horizontally over the disk for supplying fuel to and upon the disk. 110

4. An oil-burner comprising an apertured shell, a burner-disk provided with a multiplicity of openings mounted for rotation within the shell, a rotary fan disposed in spaced relation under the disk, means for discharging water upon the disk, means for effecting rotation of the disk and fan, and means including a perforated pipe provided lengthwise with a series of discharge orifices disposed horizontally over the disk for supplying combustible fuel to and upon the disk. 125

5. An oil-burner comprising an apertured shell, a fuel supply stem projecting upwardly through the shell, a burner-disk provided with a multiplicity of openings 45
 5 mounted for rotation upon the stem, a fan mounted for rotation upon the stem and disposed in spaced relation under the disk, means for discharging water upon the disk, means including a water-wheel also mounted upon the stem and having connection with the fan and disk for effecting rotation thereof, and a perforated discharge pipe provided lengthwise with a series of discharge orifices mounted upon the stem and 50
 10 disposed horizontally over the disk for supplying fuel to and upon the disk.
6. An oil-burner comprising an apertured shell, a fuel-supply stem projecting upwardly through the shell, a burner-disk having a multiplicity of openings mounted for rotation upon the stem, a fan mounted for rotation upon the stem and disposed in spaced relation under the disk, a water-coil disposed within the shell and discharging 55
 15 upon the disk, means including a water wheel also mounted upon the stem and having connection with the fan and disk for effecting rotation thereof, and a perforated discharge pipe mounted upon the stem and 60
 20 disposed horizontally over the disk for supplying fuel to the disk.
7. An oil-burner comprising a base, an apertured shell mounted upon the base, a water basin fixed within the shell, a fuel-supply stem projecting upwardly in the shell and through the basin, a tubular casting disposed within the shell for rotation upon the stem, a burner-disk provided with a multiplicity of openings fixed upon the 65
 25 casting, a fan also fixed upon the casting and disposed in spaced relation under the disk, a water wheel also carried by the casting and disposed in spaced relation under the fan, a water supply pipe discharging 70
 30 upon the wheel for effecting rotation of the casting and its carried disk and fan, a water coil disposed in the shell having communication with said water supply pipe and discharging upon the disk, a perforated discharge pipe mounted upon the stem and 75
 35 disposed horizontally over the disk for supplying fuel to the disk, and a ring-shaped casting disposed in spaced encircling relation about and partly above the plane of the shell for confining the flame of the disk.
8. An oil-burner comprising a base, an apertured shell mounted upon the base, a water basin fixed within the shell, a fuel-supply stem projecting upwardly in the shell and through the basin, a tubular casting disposed within the shell for rotation upon the stem, a burner-disk provided with a multiplicity of openings fixed upon the casting, a fan also fixed upon the casting and disposed in spaced relation under the disk, a water wheel also carried by the casting and disposed in spaced relation under the fan, a water supply pipe discharging 80
 40 upon the wheel for effecting rotation of the casting and its carried disk and fan, a water coil disposed in the shell having communication with said water supply pipe and discharging upon the disk, and a perforated discharge pipe mounted upon the stem and 85
 45 disposed horizontally over the disk for supplying fuel to the disk.

In testimony whereof, I have signed my name to this specification.

JOHN R. FLAHERTY.
